(57) **CLAIM**

The ornamental design for a tray for a scanner, as shown and described.

DESCRIPTION

FIG. 1 is a perspective view of a tray for a scanner showing our new design;

FIG. 2 is a front view thereof;

FIG. 3 is a rear view thereof;

FIG. 4 is a right side view thereof, the opposite side being a mirror view thereof;

FIG. 5 is a top plan view thereof;

FIG. 6 is a bottom view thereof; and,

FIG. 7 is a perspective view thereof, on a reduced scale. The broken line drawings of features in FIGS. 1, 5 and 6, and of the scanner in FIG. 7 are for illustrative purpose only and form no part of the claimed design.
